UNITED STATES PATENT OFFICE.

WILLIAM N. BECKETT, OF SAVANNAH, GEORGIA.

COMBINED PRIMING AND VAPORIZING DEVICE.

1,265,872.

Specification of Letters Patent. Patented May 14, 1918.

Application filed April 6, 1917. Serial No. 160,261.

To all whom it may concern:

Be it known that I, WILLIAM N. BECKETT, a citizen of the United States, residing at Savannah, in the county of Chatham and 5 State of Georgia, have invented certain new and useful Improvements in Combined Priming and Vaporizing Devices, of which the following is a specification.

My invention relates to a combined priming and vaporizing device, for use in connection with internal combustion engines, for feeding a gaseous fuel to the cylinder or cylinders thereof.

An important object of the invention is 15 to provide means for holding a liquid fuel, such as gasoline or the like, withdrawing a suitable amount of the liquid fuel and vaporizing or atomizing the same and mixing it with air, forming a gaseous explosive 20 charge, and introducing this gaseous explosive charge into the cylinder or cylinders of the engine, upon the creation of a vacuum therein, when the engine is cranked.

A further object of the invention is the 25 provision of means for preventing back pressure from the cylinder passing into the device for forcing therefrom the liquid fuel or the like.

A further object of the invention is to 30 provide means whereby the liquid fuel, as such, is not sprayed into the cylinder of the engine, as such liquid fuel tends to injure the wall or walls of the cylinders by washing off the lubricating oil therefrom.

35 Other objects and advantages of the invention will be apparent during the course of the following description.

In the accompanying drawings forming a part of this specification and in which like 40 numerals are employed to designate like parts throughout the same,

Figure 1 is a central vertical sectional view through a device embodying my invention,

45 Fig. 2 is a plan view of the same,

Fig. 3 is a central vertical longitudinal section through a second form of the invention,

Fig. 4 is a plan view of the same,

50 Fig. 5 is a central vertical longitudinal sectional view through a third form of the invention, and,

Fig. 6 is a plan view of the same.

In Figs. 1 to 6 inclusive, the numeral 10 55 designates a tubular body portion or con-

duit, having a longitudinal bore 11. At its lower end the tubular body portion 10 is provided with a flange 12, carrying a depending exteriorly screw-threaded tubular nipple 13, adapted to be screwed into an 60 opening in the head of the cylinder of the internal combustion engine.

Arranged within the tubular nipple 13 is an upwardly closing check or ball valve 14, adapted to seat upon a shoulder 15 for 65 closing the bore 11, and held against downward displacement by a transverse pin 16, as shown. It is obvious that back pressure seats the valve 14 and therefore the back pressure cannot pass into the bore 11. 70

The tubular body portion 10 is provided with a transverse preferably tapered opening 17, intersecting the bore 11 and receiving a tapered rotatable valve 18, which is turned by a crank 19. The opposite end 75 of the valve 18 has a shank 20, and the valve 18 is held securely upon its tapered seat 17 by a compressible coil spring 21, as shown. The valve 18 is provided with a transverse opening or port 22 adapted for 80 movement into and out of registration with the bore 11. It is thus apparent that the valve is provided for partly or wholly closing or opening the bore 11. 75

Secured to the upper end of the tubular 85 body portion 10 and preferably formed integral therewith is a cup-shaped liquid fuel holding receptacle 23, the upper end of which is open, as shown.

In Figs. 1 and 2, the numeral 24 designates a vertically arranged air supply pipe, having its lower end screw-threaded into the upper end of the bore 11, as shown at 25. The air supply pipe 24 extends longitudinally through the receptacle 23 but has 95 no direct communication therewith, as its upper end is disposed a substantial distance above the receptacle. Connected with one side of the air supply pipe 24 is a branch pipe 25', serving as a siphon, and having 100 its lower end open, and disposed in the lower portion of the receptacle 23 beneath the level of the liquid fuel therein.

In Figs. 3 and 4, the numeral 26 designates a vertically arranged air supply pipe having 105 its upper end open and disposed a substantial distance above the receptacle 23 and this pipe 26 extends through the receptacle and is screw-threaded into the upper end of the bore 11, as shown at 27. An inverted 110

approximately U-shaped pipe 28, has one end thereof connected with the pipe 26 near its lower end, while the upper portion of the pipe 28 is arranged above the receptacle 23, and its lower intake end is disposed within the receptacle below the liquid level therein.

In Figs. 5 and 6, a single approximately U-shaped pipe 29 is provided, having its free end arranged within the receptacle 23 below the liquid level thereof, while its upper portion is disposed above the receptacle and its opposite end is screw-threaded within the upper end of the bore 11, as shown at 30. The pipe 29 is apertured or provided with an opening 31, which is arranged above the receptacle 23 and the level of the liquid therein.

In the operation of the form of apparatus shown in Figs. 1 and 2, when the valve 18 is opened, and the engine is cranked, upon the down stroke of the piston, a vacuum will be created in the cylinder, and air drawn inwardly through the air supply pipe 24. The air traveling through the pipe 24, in proximity to the discharge end of the branch pipe 25 creates a sufficient suction therein, for drawing a proper amount of the liquid fuel from the receptacle 23. This liquid fuel is sprayed into the pipe 24 in the presence of the downward traveling air and becomes thoroughly mixed therewith to be discharged into the cylinder of the engine.

The operation of the form of apparatus shown in Figs. 3 and 4 is thought to be so similar that no further explanation thereof is thought necessary.

In the operation of the form of apparatus shown in Figs. 5 and 6, the suction in the bore 11 serves to draw air in through the pipe 29, such air entering at the opening 31. The air entering at the opening 31 creates a suitable suction within the lower portion or free end 29' of the pipe 29, which corresponds to the pipe 25', and may be considered as an extension of the pipe 29, and this suction draws up a sufficient amount of liquid fuel which becomes mixed with the air and is fed to the cylinder of the engine.

It is to be understood that the forms of my invention herewith shown and described are to be taken as preferred examples of the same, and that various changes in the shape, size, and arrangements of parts may be resorted to without departing from the spirit of the invention or the scope of the subjoined claims.

Having thus described my invention, I claim:

1. A device of the character described, comprising a tubular body portion for connection with an engine cylinder or the like, a liquid fuel holding receptacle connected with one end of the tubular body portion

and having no direct communication therewith, and an air supply pipe passing through the liquid fuel holding receptacle with one end thereof discharging into the tubular body portion and having an extension projecting downwardly into the receptacle with the intake end of such extension arranged beneath the level of the liquid fuel therein.

2. A device of the character described, comprising a tubular body portion for connection with an engine cylinder or the like, a liquid fuel holding receptacle connected with the tubular body portion and having no direct communication therewith, an air supply pipe extending longitudinally through the liquid holding receptacle and having one end thereof disposed above the maximum liquid level thereof and in communication with the atmosphere and its opposite end discharging into the tubular body portion and having no direct communication with the liquid fuel holding receptacle, and a liquid fuel take-up pipe secured to the air supply pipe with a portion thereof disposed above the maximum liquid level within the receptacle and having its intake end arranged in the lower portion of the receptacle below the liquid level thereof.

3. A device of the character described, comprising a tubular body portion for connection with an engine cylinder, a liquid fuel holding receptacle connected with the outer end of the tubular body portion and having no direct communication therewith, an air supply pipe extending through the receptacle with one end thereof in communication with the atmosphere and its opposite end connected with the tubular body portion, and a liquid fuel take-up pipe secured to the air supply pipe at a point above the maximum level of the liquid fuel in the receptacle, and having its intake end arranged within the lower portion of the receptacle.

4. A device of the character described, comprising a tubular body portion having connection with an engine cylinder or the like, a liquid fuel holding receptacle connected with the tubular body portion and having its top open, an air supply pipe extending longitudinally through the liquid fuel holding receptacle with its lower end extending into the bore of the tubular body portion and having no direct communication with the liquid fuel holding receptacle and its upper end extending above the maximum liquid level of the receptacle, and a liquid fuel take-up pipe connected with the air supply pipe and having its intake end arranged within the receptacle beneath the maximum liquid level thereof.

5. A device of the character described, comprising a tubular body portion having connection with an engine cylinder or the like, a liquid fuel holding receptacle connected with the tubular body portion and

having no direct communication therewith, an air supply pipe passing through the liquid fuel holding receptacle with one end thereof discharging into the tubular body portion and having an extension projecting downwardly into the receptacle with the intake end of such extension arranged beneath the level of the liquid fuel therein, and a check valve to prevent back pressure from 10 passing through the tubular body portion.

6. A device of the character described, comprising a tubular body portion having connection with an engine cylinder or the like, a liquid fuel holding receptacle connected with the tubular body portion and having no direct communication therewith, an air supply pipe passing through the liquid fuel holding receptacle with one end thereof discharging into the tubular body 15 portion and having an extension projecting downwardly into the receptacle with the intake end of such extension arranged beneath the level of the liquid fuel therein, and a separate cut-off valve connected with the 20

tubular body portion and disposed outwardly of the check valve. 25

7. A device of the character described, comprising a tubular body portion adapted for connection with the cylinder of an engine or the like, a liquid fuel holding receptacle connected with the body portion, a curved pipe having one end extending into the tubular body portion and its opposite end discharging into the receptacle beneath the liquid level thereof, said pipe having an 30 air inlet aperture disposed above the maximum liquid level of the receptacle, a check valve to prevent the passage of back pressure into the tubular body portion, and a cut-off valve associated with the tubular 35 body portion. 40

In testimony whereof I affix my signature in presence of two witnesses.

WILLIAM N. BECKETT.
